United States Patent

Des. 237,548
Patented Nov. 4, 1975

237,548

BLOOD GAS ANALYZER AND THE LIKE

Dean T. Farrish, Parker, Colo., assignor to
Sandoz, Inc., East Hanover, N.J.

Filed Jan. 10, 1974, Ser. No. 432,143

Term of patent 14 years

Int. Cl. D24—01

U.S. Cl. D83—1 F

FIG. 1

FIG. 2

FIG. 3

FIG. 4

FIG. 1 is a front elevation view of a blood gas analyzer and the like;

FIG. 2 is a right side elevation view of the blood gas analyzer and the like, looking from the right in FIG. 1 with respect to the longitudinal dimension;

FIG. 3 is a rear elevation view of the blood gas analyzer and the like, looking from the rear of FIG. 1;

FIG. 4 is an isometric view of the blood gas analyzer and the like.

I claim:

The ornamental design for a blood gas analyzer and the like, as shown.
